UNITED STATES PATENT OFFICE

97,134

DESIGN FOR AN AUTOMOBILE SEAT SLIP

Roman Jaramillo, El Rito, N. Mex.

Application May 16, 1935, Serial No. 56,876

Term of patent 7 years

To all whom it may concern:

Be it known that I, Roman Jaramillo, a citizen of the United States, residing at El Rito, in the county of Rio Arriba and State of New Mexico, have invented a new, original, and ornamental Design for an Automobile Seat Slip, of which the following is a specification, reference being had to the accompanying drawing, forming part thereof.

The figure is a plan view of an automobile seat slip, showing my new design.

I claim:—

The ornamental design for an automobile seat slip as shown.

ROMAN JARAMILLO.
